UNITED STATES PATENT OFFICE

EMIL SCHNABEL, OF DESSAU IN ANHALT, AND FRIEDRICH A. W. KÜHNE, OF MANNHEIM, GERMANY, ASSIGNEES TO I. G. FARBENINDUSTRIE AKTIENGESELLSCHAFT, OF FRANKFORT-ON-THE-MAIN, GERMANY

IMPREGNATING WEBS, CLOTHS AND FABRICS

Application filed April 11, 1930, Serial No. 443,439, and in Germany March 1, 1929.

Our present invention relates to a process for impregnating webs and to a device for carrying out the said process.

It is well known in the art to impregnate webs of fibrous material such as, for instance, tissues, textile fabrics, felt, paper or the like with suitable solutions such as, for instance, solutions of resins or cellulose derivatives, by passing the sheet to be impregnated over a special table and applying the impregnating solution thereon from above by means of an atomizer or a pouring device. This process presents the disadvantage of allowing only part of the air bubbles contained in the web 15 to escape upwardly in consequence of the high viscosity of the impregnating solution, so that the impregnated web, when the impregnating liquor has solidified, contains air bubbles.

According to our present invention, impregnated webs free from air bubbles, are obtainable in a simple manner by removing the air contained in the web of fibrous material by means of solvent vapors before the web comes in contact with the impregnating liquor. Preferably, vapors of such solvents are used as are contained in the impregnating liquor. The web may, for instance, be passed through a chamber charged with vapors of solvents and heated, if desired, immediately before the impregnating liquor is applied on to the web. This removal of the air and the impregnation of the web can also be carried out in one working operation. 30 This can be done by applying the impregnating liquor from below and thus utilizing the solvent vapors evolved by the liquor itself. The impregnating liquor penetrating into the web from below is preceded by a layer of solvent vapors driving out the air, enclosed in the interstices between the single fibers, in an upward direction and thus ensures a complete impregnation of the web without any air bubbles being left therein.

Also if the vapor tension of the impregnating liquor be only relatively small, the air is practically completely driven out from the web because, by the action of the impregnating liquor which rises from below, it is forced 45 upwardly where it may freely escape.

Furthermore, the new impregnating process may be completed, if desired, by applying, according to known methods, a further impregnating liquor on the upper surface of the web before the impregnating liquor applied to the lower surface has been dried. For this purpose either the same or another 55 impregnating liquor may be used.

The process can be conducted with the aid of all devices which allow the impregnating liquor to be carried to the lower surface of the web of fibrous material. Preferably, however, a known drum- or a band pouring machine is used, in which the impregnating liquor is poured, by means of a film-casting 60 funnel having a slit of corresponding breadth on a uniformly moving solid support which is provided with guide-devices for the web. These guide-devices, for instance, suitable rollers or the like, lead the web to the exit-slit of the film-casting funnel or to a place 65 immediately behind it, so that the web to be impregnated lies closely on the layer of impregnating liquor flowing out of the funnel. The web can be guided to the film-casting 70 slit, for instance, in such a manner that it is caused to slide downwardly at the front wall of the funnel, while lying closely and uniformly on the inner side thereof and then to reach the conveyer band or the drum carrying the impregnating liquor, so that it lies 75 closely on the out-flowing liquor. Since, when simply guiding the web through the funnel, the danger exists that it is prematurely soaked with the liquor and the air bubbles 80 driven out thereof enter the latter, it is recommended to provide for this process a particular funnel having a double front wall through which the web passes without touching the impregnating liquor before the exit 85 of the liquor supplying device.

Fig. 1 of the drawing diagrammatically illustrates our new process and the apparatus which preferably may be used.

The web I to be impregnated is reeled off 90 from the winding drum A and passes over guide rollers a receptacle B which is filled with vapors of organic solvents. From this receptacle which, if necessary, may be avoided, the web is guided over rolls to the slit 100

of a film-casting funnel C arranged above the conveyer band G of a film-casting machine.

Fig. 2 shows an embodiment of the funnel in section. The impregnating liquor F is filled into the film-casting funnel C from which it flows to the conveyer band G through the slit H. The funnel C has a double front wall formed by the plates E and D through which the web I is guided to the slit H of the funnel C, which may be adjusted by means of a hand wheel K. The plates D and E are parallel to each other and distanced, so that the web to be impregnated may be guided through the formed interstice.

The process of impregnating may also be performed with the use of a film-casting funnel not provided with a double front wall, by guiding, for instance, the web by means of rollers closely in front of the slit of the funnel.

After having passed the outlet H of the funnel C, the conveyer band G is covered with a thin layer of the impregnating liquor which on the forward movement continuously enters the web I lying closely thereon.

The webs to be impregnated may be woven of animal or vegetable, natural or artificial fibers as, for instance, cotton, wool, silk, jute, ramie, nettle, artificial silk and so on.

As an impregnating compound, we may use cellulose derivatives, natural or artificial resins, guttapercha, balata, caoutchouc, and so on, or mixtures of these products, if necessary, with addition of oils, softening or filling agents, pigments or dyes. In preparing the impregnating liquids, we may use the organic solvents, known in the art, preferably acetone, benzene or halogenated hydrocarbons.

The thickness of the layers to be applied to the webs may vary between 1 to 3000 μ , preferably, layers of about 50 μ and more are produced. Obviously, the thickness depends upon the concentration of the impregnating liquid and on the opening of the film-casting funnel. The temperature of the impregnating liquid may be varied within wide limits; the same holds true with regard to the support on which the layer of impregnating liquid is cast. Too high temperatures, however, are preferably avoided. By a suitable selection of the solvent, temperature, concentration and viscosity of the impregnating liquor, any desired impregnation, free from air bubbles, may be performed. The layer applied to the web may be dried by warming the support carrying it or by blowing warm air over the impregnated fabric. These specific details and the recovery of the solvents likewise are well known from the industry dealing with the manufacture of celluloid films or oilcloth.

Numerous other embodiments of our invention are possible and we contemplate as included within our invention all such modi-

fications and equivalents as fall within the scope of the appended claim.

What we claim is:—

A device for impregnating webs, cloths and fabrics comprising a support for the material to be impregnated and a funnel for casting a uniform layer of the impregnating solution on the said support, a double front wall on said funnel for guiding the material to be impregnated and for imposing it on the layer of impregnating solution formed immediately at the exit of the said funnel.

In testimony whereof, we affix our signatures.

EMIL SCHNABEL.
